HYDRAULIC FEEDER DEVICE FOR WORKPIECES OF MACHINE TOOLS

Eugène Monnier, Safnern, Switzerland, assignor to
Fabrique de Machines Mikron S.A., Bienne, Switzerland,
a corporation of Switzerland

Filed May 22, 1962, Ser. No. 196,676

Claims priority, application Switzerland May 24, 1961
5 Claims. (Cl. 214—1)

The present invention has for its object a hydraulic feeder device, more particularly for the setting in place of a workpiece to be machined on a machine-tool comprising a fixed frame, integral with the machine-tool, in which a member is disposed oscillating between two distinct angular positions. This oscillating member comprises two catcher members, one fixed and the other radially displaceable with respect to this oscillating member. The two catcher members are angularly spaced from each other, while the oscillating member and the mobile catcher member are hydraulically actuated, the former in its reciprocative angular movements and the latter in its rectilinear displacements.

The attached drawing shows schematically and by way of example one embodiment of the feeder device according to the invention.

FIG. 1 is an elevational view of this embodiment, partially in cross-section, the device being in its start or rest position.

FIG. 2 is another elevational view, partially in cross-section, the device being in its loading position.

FIG. 3 is a plan view, the device being in the position corresponding to the one illustrated at FIG. 1, the mobile catcher member being in its position illustrated in dash lines.

The hydraulic feeder device shown comprises a frame 1 integral with the machine-tool to be fed, an oscillating member 2 pivoted with respect to the frame 1 and a device for hydraulically actuating said oscillating member 2.

The frame 1 comprises a charger 3 vertically disposed and intended to house pieces 4 to be machined. This charger is removably secured to the frame for example by means of a tightening member 5. A housing 6, presenting in transverse cross-section general shape of a sector of a circle, is provided inside the frame 1. This housing is intended to receive the oscillating member 2 when the latter member is in its rest position. The lower frontal face 7 of the charger 3 is disposed tangentially with respect to this housing 6.

The transverse cross section of the oscillating member 2 has the general shape of a sector of a circle of about 90°, the inner diameter of which corresponds to the diameter of the housing 6. The oscillating member is pivoted around an axis 8 identical to the axis of revolution of the cylindrical surface surrounding this oscillating member.

This oscillating member 2 comprises a fixed catcher member constituted in the example shown by a bracket 9 and a flexible blade 10 fixed by one of their extremities on the oscillating member, in such a way that their free extremities are located on the said cylindrical surrounding surface. The shape of the bracket 9 is such that it determines with the flexible blade 10 a housing 11 intended to receive a non machined or rough piece 4. This housing is disposed, when the oscillating member 2 is located in the rest position, along the prolongation of the vertical axis of the charger 3.

The oscillating member 2 is also provided with another catcher member displaceable along a radius of said oscillating member. This latter catcher member is constituted

2

in the example shown by a piston 12, displaceable inside a cylinder 13 against the action of a spring 18. This cylinder 13 is alternatively connected, through the intermediary of a duct passing inside the axis 8 and a three way valve, to a supply of fluid under pressure and to the discharge. This piston 12 carries a rod 14 provided with a clamp 15 presenting in transverse cross-section the general shape of a U. One of the wings 16 of said clamp 15 is flexible. The distance separating the two wings of this clamp 15 is slightly less than the diameter of a machined piece 17.

An abutment 19, integral with the frame 1 defines the angular rest position (FIG. 1) of the oscillating member 2.

15 The device for actuating the oscillating member 2 comprises a cylinder 20 disposed in the frame 1, inside which a piston 21 moves. The lower extremity 22 of the piston 21 co-operates with a lever 23 pivoted on the frame 1 and integral with a toothed sector 24, the toothing of which is in mesh with a toothed wheel 25 integral with the pivoting axis 8.

The cylinder 20 is provided with an opening alternatively connected for example by means of a slide-valve, to a supply of fluid under pressure and to a discharge container.

25 A spring 26 tends to maintain the piston 21 in a position such that the oscillating member will be in its rest position.

This hydraulic feeding device further comprises 30 discharge means for discharging the machined pieces. These means are constituted, in the example illustrated by a conveyor, the band 27 of which is displaced in an intermittent way in the direction of the arrow f (at a rate of one forwarding step or pitch for each reciprocation of the piston 21) by means of a mechanical linkage having only one direction of displacement. The aforementioned linkage is constituted for example by a wheel with ratching teeth 28 meshing with a pusher 29 carrying a toothed maintained by an elastic action in mesh with the wheel 28. This pusher is mechanically connected to the lever 23.

The feeder device described and illustrated in mounted by way of example, on a milling machine provided with two supporting members 30, 31 for the retaining of the piece to be machined in its machining position on the milling machine. When the piece to be machined is clamped on the machine, it is situated over the milling cutter 32.

50 During the machining of a piece on a milling machine, the feeder device is in the rest position shown in FIG. 1. When the machining of the piece held in the supporting members 30, 31 is terminated, the following operations are effectuated:

55 (1) By actuating the three way valve, the cylinder 13 is set under pressure which causes the forwarding of the piston 12, and the displacement of the mobile catcher member from its position illustrated in full lines into its position illustrated in dashed lines (FIG. 1). In this latter position, the machined piece 17 held by the supporting members is clamped between the two wings of the clamp 15.

(2) The machined piece 17 is freed from the supporting members 30, 31 by an automatic device of known type, not shown.

(3) The feeding of the cylinder 13 is interrupted and it is then connected to the discharge by actuating the three way valve. The piston 12 returns to its rest position for which the clamp 15, taking the machined piece 17 along in its movement, is no longer located over the milling cutter 32.

(4) The slide-valve is actuated by any known means, not represented, in order to feed the cylinder 20 with fluid under pressure, which causes the downward displacement of the piston 21 into its position illustrated in FIG. 2. This movement of the piston 21 causes, through the intermediary of the mechanical linkage 23, 24, 25, the rotation of the oscillating member by 90° and, through the intermediary of the mechanical linkage 23, 28, 29, the forwarding of the conveyor.

After this displacement the oscillating member 2 is situated in its loading position, illustrated at FIG. 2. In this position the fixed catcher member carrying a rough piece 4 to be machined is situated in such a way that it may be fixed on the machine by means of the supporting members 30, 31. Further in this position the wing 16 of the clamp 15 of the displaceable catcher member is elastically displaced in the direction of the arrow *g* by means of an abutment 33 integral with the frame 1, which releases the machined piece 17 so that it falls on the conveyor.

(5) The rough piece 4 is automatically held in the supporting members 30, 31 in a known manner.

(6) The cylinder 20 is again connected to the discharge by actuating the slide-valve. The piston 21 is returned to its rest position by the spring 26, which produces the rotation of the oscillating member 2 in the reverse direction of 90° and puts it back in the rest position (FIG. 1).

The piece 4 to be machined fixed in the supporting members is disengaged during this movement from the fixed catcher member. In fact, this piece escapes the flexible blade 19. At the end of the movement the fixed catcher member is again located in front of the lower extremity of the charger 3 and a new piece 4 to be machined falls through gravity into this fixed catcher member.

The same operations are repeated each time the machining of a piece is terminated.

The hydraulical feeder device according to the invention enables the setting in place of a piece to be machined and simultaneously the withdrawal of a machined piece.

Further this device presents the great advantage to enable the automatic feeding of a machine-tool the cutting-tool of which is located under the piece to be machined.

One embodiment of the device, object of the invention, has been described by way of example but it is to be understood that numerous variants of execution may be foreseen without departing from the scope of the protection claimed. Particularly, the realization and the shape given to both the fixed catcher member and the linearly displaceable catcher member could be, in variants, different. In fact, the shape of these catcher members is dictated by the shape of the piece being handled, and it is apparent that many realizations are possible without departing from the scope of the protection claimed.

I claim:

1. A hydraulic feeder and take-off device for setting a workpiece in place on a machine tool having a rotating spindle, said feeder device comprising a fixed frame integral with said machine tool, charging means and discharging means for said workpiece disposed adjacent said rotating spindle, an oscillating member angularly displaceable between two extreme angular positions, a first catcher member rigidly mounted on said oscillating member, a second catcher member carried by said oscillating member and angularly spaced apart from said first catcher member at an angle equal to the angle between said two extreme angular positions, said second catcher member being radially displaceable with respect to said oscillating member between a retracted position and a forwarded position, said first catcher member registering with said charging means and said second catcher member registering with the axis of said spindle when said oscillating member is in one of said two extreme angular positions, said first catcher member registering with

the axis of said spindle and said second catcher member registering with said discharging means when said oscillating member is in the other extreme angular position, and hydraulic actuating means for controlling the angular reciprocating movements of said oscillating member between said two extreme angular positions and the rectilinear reciprocating movements of said second catcher member between said retracted position and said forwarded position.

2. A device as claimed in claim 1, wherein the angle between said two extreme angular positions of the oscillating member equals 90° and the angular spacing of said first and said second catcher members is 90°.

3. A hydraulic feeder and take-off device for setting a workpiece in place on a machine tool having a rotating spindle, said feeder device comprising a fixed frame integral with said machine tool, charging means and discharging means for said workpiece disposed adjacent said rotating spindle, an oscillating member angularly displaceable between two extreme angular positions, a first catcher member rigidly mounted on said oscillating member and arranged to carry a rough, nonmachined workpiece, said first catcher member comprising a rigid bracket and a flexible blade together forming a housing for said rough workpiece, said flexible blade applying an elastic pressure to the rough workpiece located in said housing to retain it therein, a second catcher member carried by said oscillating member and angularly spaced apart from said first catcher member at an angle equal to the angle between said two extreme angular positions, said second catcher member being radially displaceable with respect to said oscillating member between a retracted position and a forwarded position, said second catcher member comprising a clamp with a U-shaped form, one wing of said clamp being elastically displaceable to retain a machined workpiece therein by elastic pressure, said first catcher member registering with said charging means and said second catcher member registering with the axis of said spindle when said oscillating member is in one of said two extreme angular positions, said first catcher member registering with the axis of said spindle and said second catcher member registering with said discharging means when said oscillating member is in the other extreme angular position, and hydraulic actuating means for controlling the angular reciprocating movements of said oscillating member between said two extreme angular positions and the rectilinear reciprocating movements of said second catcher member between said retracted position and said forwarded position.

4. A device as claimed in claim 3, wherein said discharging means comprises an abutment means for releasing the elastic pressure of said clamp upon said machined workpiece and a hydraulically actuated conveyor carrying the released machined workpiece away from said machine tool.

5. A hydraulic feeding and take-off device for setting workpieces in place upon a machine tool having a rotatable spindle, said device comprising a fixed frame integral with the machine tool, charging means for providing rough, nonmachined workpieces, discharging means for removing the machined workpieces, an oscillating member angularly reciprocated between two predetermined spaced positions, two catcher members carried by said oscillating member and separated from each other at an angle equal to the angular spacing of said predetermined positions, means for rigidly mounting one of said catcher members on said oscillating member, means for displacing the other catcher member radially with respect to said oscillating member between a retracted position and a forwarded position, said other catcher member thereby displacing machined workpieces away from the axis of said spindle, and hydraulic means for rotating said oscillating member from one of said positions to its other position in which the next rough workpiece is positioned on the axis of said spindle while the

workpiece just machined is simultaneously transported to
said discharging means.
